(57) **CLAIM**

The ornamental design for a floor drain, as shown and described.

DESCRIPTION

FIG. 1 is a top perspective view of a floor drain design showing our new design.

FIG. 2 is a front view of a floor drain.

FIG. 3 is a rear view of a floor drain.

FIG. 4 is a left side view of a floor drain.

FIG. 5 is a right side view of a floor drain.

FIG. 6 is a top view of a floor drain.

FIG. 7 is a bottom view of a floor drain.

FIG. 8 is a bottom perspective view of a floor drain; and, FIG. 9 is another top perspective view of a floor drain.

The broken lines in the drawings depict portions of the floor drain that form no part of the claimed design.

The broken lines depict portions of the floor drain that form no part of the claimed design.
